UNITED STATES PATENT OFFICE.

WILLIAM H. CLENDENON, OF HEALDSBURG, CALIFORNIA.

WIRE-FENCE STRETCHER.

No. 831,038.

Specification of Letters Patent.

Patented Sept. 18, 1906.

Application filed June 19, 1906. Serial No. 322,464.

To all whom it may concern:

Be it known that I, WILLIAM H. CLENDENON, a citizen of the United States, residing at Healdsburg, in the county of Sonoma and State of California, have invented a new and useful Wire-Fence Stretcher, of which the following is a specification.

This invention relates to wire-fence stretchers.

10 The object of the invention is to provide an extremely strong, simple, durable, inexpensive, and thoroughly efficient device by means of which the wires of a fence can be easily and quickly stretched in order to enable them to be properly secured upon the fence-posts.

With the foregoing and other objects in view, which will appear as the description proceeds, the invention resides in the combination and arrangement of parts and in the details of construction hereinafter described and claimed, it being understood that changes in the precise embodiment of invention herein disclosed can be made within the scope of the following claims without departing from the spirit of the invention or sacrificing any of its advantages.

In the accompanying drawings, forming part of this specification, Figure 1 is a side elevation showing part of a fence in order to illustrate the manner of using the improved device. Fig. 2 is a perspective view of the device. Fig. 3 is a vertical section.

Like reference characters indicate corresponding parts in the different figures of the drawings.

The improved wire-fence stretcher of this invention comprises a body portion or member A and a handle B.

40 The member A is formed in its upper surface with a longitudinally-extending open-ended slot 1, which is approximately V-shaped in cross-section. If it be supposed that the device is held with the handle B extending vertically upward, one wall 2 of the slot 1 will be disposed in approximately vertical position, so as to be parallel or nearly parallel with the side walls 3 of the member A. The other wall 4 of the approximately 45 V-shaped slot 1 extends at an incline with respect to the parallel walls 3 of the member A.

50 The handle B is suitably connected with or formed integral with the upper portion of the straight or approximately vertical wall 2 of the member A at one end thereof. The handle B is formed with an abutment 10,

which extends laterally across the broad upper end of the slot 1, so as to produce an entrance portion 11 between the upper edge of the inclined wall 4 and the adjacent portion 60 of the abutment 10. The lower wall 12 of the abutment 10 is cut on a slight downward incline with respect to the straight vertical wall 2 of the slot 1, so as to form, in effect, a wire-receiving notch at the juncture 65 of the wall 12 with the upper portion of the wall 2. The handle B preferably is tapered from the abutment 10 upward and is provided adjacent its upper end with a perforation 14, constituting attaching means for a 70 flexible element 15, which is suitably secured at its other end to an intermediate portion of a lever 16.

In using the improved device the line-wire 17 of a fence is passed through the lateral 75 entrance portion 11 of the slot 1. The lever 16 is then engaged with a fence-post or other object and rocked or manipulated so that the handle B will be drawn rearwardly. This rearward movement of the handle will 80 cause one portion of the wire to be pinched or gripped in the V-shaped lower end of the notch 1 and another portion of the wire to be engaged by the wire-receiving notch formed by the lower wall or shoulder 12 of the abutment 10 and the straight or vertical wall 2. In this way an intermediate portion of the wire will be bent so as to cause the same to be stretched, and thus permit it to be nailed or otherwise secured upon the post. The 85 handle B preferably is disposed at an angle slightly less than a right angle with respect to the member A, so that the lateral entrance portion 11 will extend obliquely across one side of the handle, as shown. The 90 lower rear end of the member A preferably is rounded, as indicated at 20, and the upper end of the handle B is rounded, as indicated at 21.

By reason of the fact that the entire device of this invention can be formed of a single piece of material and, further, by reason of the fact that the slot 1, with its lateral entrance portion 11, can be readily formed it will be obvious that the wire-fence 100 stretcher of this invention is extremely simple and inexpensive in construction. Furthermore, it has been found to be thoroughly efficient in operation. The forward end of the V-shaped slot 1 constitutes a wire-receiving portion which pinches the wire and prevents it from slipping, and the abutment 105 110

10, with its downwardly-inclined lower wall 12, forms a wire-receiving notch which, as before explained, effectually coöperates with the wire-receiving portion of the member A, 5 so as to permit a wire to be easily and quickly stretched.

What is claimed is—

1. A wire-fence stretcher comprising a member having a wire-receiving slot, and a 10 handle extending at an angle to said slot, the length of said wire-receiving slot being greater than the width of said handle.
2. A wire-fence stretcher comprising a member having a wire-receiving portion at 15 one end thereof and a handle extending at an angle with respect to the opposite end of said member and having a wire-engaging abutment projecting over one end of said member.
3. A wire-fence stretcher comprising a 20 member having a V-shaped notch in one end, and an angularly-extending handle connected with the other end of said member and having an abutment forming a wire-receiving notch.
- 25 4. A wire-fence stretcher comprising a member having a slot which is approximately V-shaped in cross-section, and a han-

dle having an abutment extending across the upper end of said slot and terminating above one wall thereof to form a lateral entrance 30 portion for said slot.

5. A wire-fence stretcher comprising a member having a wire-receiving slot in its upper surface formed with an approximately vertical wall, which is parallel with the sides 35 of said member, and another wall which is inclined with respect to the sides of said member, an upwardly-extending handle connected with one end of the straight wall of said slot and having an abutment formed 40 with a downwardly-inclined lower wall terminating above the inclined wall of said slot so as to produce a lateral entrance portion, said handle being disposed at an angle which is slightly less than a right angle with respect 45 to said member.

In testimony that I claim the foregoing as my own I have hereto affixed my signature in the presence of two witnesses.

WILLIAM H. CLENDENON.
